UNITED STATES PATENT OFFICE.

SIMON E. SCHROEDER, OF OAK PARK, ILLINOIS.

SAFETY-WRINGER MECHANISM.

Application filed July 24, 1922. Serial No. 576,973.

My invention relates to wringers and more particularly to safety mechanism for the so-called wood frame wringers.

The object of my invention is in the provision of a safety mechanism for a wringer, whereby the striking of a conveniently located handle releases the tension on the upper roll of the conventional wringer.

Another object of my invention is in the provision of a safety mechanism in connection with the so-called wooden frame wringer, whereby release of the safety mechanism automatically releases the upper tensioned wringer roll but does not result in the disengagement or throwing out, from the wringer, of any part of said safety mechanism.

My invention contemplates a safety release mechanism simple and efficient and which will overcome the great disadvantage of the safety mechanisms usually employed in the type of so-called wooden frame wringer, that is, upon release of the safety mechanism, either the hurling entirely from the machine of parts of the safety mechanism or such disengagement that makes necessary a replacement of various parts. Operators of washing machines or wringers usually lack mechanical skill and no matter how simple the replacement of portions of a safety mechanism, after release may be, there is undoubtedly confusion.

My present safety mechanism permits instant release of the upper wringer roll and a very small amount of adjustment to replace said wringer in its normal operating position.

Other objects of my invention will appear in the following specification in connection with the annexed drawings in which:

Figure 1, is a plan view of the wringer.

Figure 2, is a side elevation thereof.

Figure 3, is a rear elevation.

Figure 4, is an enlarged detail of the release handle and connected portions, and

Figure 5, is an enlarged detail of my particular release mechanism.

Referring to the drawings, in Figure 2, is shown a conventional wringer, capable of being used with most types of washing machines. Inasmuch as my invention is directed mainly to the safety mechanism of the wringer, I have not deemed it necessary to include even power connections with the washer.

A power shaft 10 has connection with the power plant of a washing machine not shown. A power roll 11 has connection with the power shaft and is mounted in the conventional manner in the frame portions 12 of the wringer. The wringer itself being conventional, I am not including a detailed description thereof and merely indicate at 13, a housing member which encloses the conventional gears, not shown, which permit motion being transmitted from the lower power roll to the removable upper wringer roll 14. The upper or tension wringer roll 14, has at either end bearing blocks 15, which are slidable in guide ways in the frame portions 12. In these guide ways are mounted the tensioning springs 16, which engage, at their lower portion, lugs 17, on the bearings 15.

My safety mechanism is mounted entirely in the head portion 18, of the wringer and is made up of the following portions:

Pivottally mounted at 19, in the head portion, are brackets 20, slidable in cut-out portions in the head. These brackets have at their outer ends the receiving portions 21, which have inserted therein, the tensioning screws 22. Lugs 23, inserted in the upper portions of the tensioning springs 16, abut the lower end of the screw members. Brackets 20, as shown in the enlarged detail in Figure 5, are formed in such manner that a lower projecting portion 24, thereof, extends, in its normal position, as shown in full lines in said figure, slightly below the head portion. A catch 25, is formed in this lower portion and is capable of receiving a release arm to be described later.

I have shown at 26, a release handle which may be of any desired form. From handle 26 depends the pin member 27, the same being pivotally seated in head member 18 and having positively attached thereto, as at 28, a short bar 29. This short bar has pivotal connection at 30, with the releasing arms 31, which are capable, at their outer end, of engagement with the catches 25, on the brackets 20. At 32, are shown guide and support members for the releasing arms and it may be noticed that these members are wide enough to permit sliding of the arms 31, even in the distorted position shown in dotted lines in Figure 4. A small lug 33 is shown on the lower portion 24, of the brackets 20, and this lug, as shown in the dotted line position in Figure 5, abuts the

lower side of the head portion when the safety mechanism has been released and thus prevents the released tensioning springs from throwing the brackets entirely from the head portion and, as a matter of fact, permits sufficient release of the upper wringer roll 14, but does not allow the various portions of the safety mechanism to be disengaged to such an extent that a great deal of adjustment is required in replacement. Stop 34, is disposed upon the lower face of head member 18 and lies in the path of the short bar 29 and serves to prevent said bar from being thrown into a reverse acting position.

15 The operation of my safety mechanism for wringers is as follows:

In Figure 2, in heavy lines, is shown the normal positioning of my mechanism with the brackets 20, lying longitudinally of the head portion and with the releasing arms 31, engaging the catch portions in the brackets 20. The releasing arm extends longitudinally of the head portion at this time. Such positioning of the releasing levers and brackets 20, permits adjustment of the tensioning screws 22, upon the tensioning springs 16, to hold the upper wringer roll 14, in its correct tensioned relation with the lower power roll 11. It may be seen that any tension that is desired is permitted by either screwing or unscrewing of the members 22. Should it be desired to release the safety mechanism, the handle member 26, is struck by the operator's hand in such a manner that it will be drawn to an off-centered position, or lie in such manner that the short bar 29, will be turned at an angle to withdraw the releasing arms 31, from the catches 25, in the brackets 20, thus permitting the release of the tensioning springs 16, and thereby, the upper wringer roll 14. The lugs 33, do not permit the tensioning springs 16, from being thrown entirely from the frame members and even in their released condition, they necessarily abut the receiving ends 21, of the brackets.

In order to return the safety mechanism to its normal position, it is merely necessary to unscrew the members 22, in the receiving portions 21, until the brackets lie normally in their cut-out portions in the head. The length of the tensioning springs and form of the brackets 20, permit the lower portions 24, of said brackets to assume their normal position, and thereupon the releasing handle 26, is returned to its normal position, that is, longitudinally of the head and the releasing arms are again thrown into engagement with the catch portions on the brackets. All that is necessary now is to re-tension the screw members 22, and therefore the tensioning springs and upper wringer roll, with the result that the wringer is again in normal and operative position.

What I claim is:

65 1. In a device of the class described, in

combination, frame members, a power roll, an upper roll, spring members mounted in the frame members and applying pressure on the outer ends of said upper roll, a head portion, members having catch portions pivoted on said head portion intermediate of the center and ends thereof and having their outer ends provided with means for engaging said spring members, means for normally holding said pivoted members so as to compress said spring members including arms on said head portion engaging catch portions on said pivoted members and means for releasing said pivoted members from said arms.

2. In a wringer, in combination, a frame including side framing members, a stationary roll, a movable roll, spring members supported in the side framing members in position to resiliently press on the movable roll, a head member attached to the side framing members, members pivoted on the head member intermediate the center and ends thereof, each provided with depending hooked portions, screw members in the pivoted members adapted to abut the springs, means for effecting engagement or disengagement of the head and the pivoted members including a release handle rotatably mounted on the head intermediate the pivoted members, arms engageable with the hooked portions of the pivoted members and means connecting the release handle and arms whereby the turning movement of the former will effect release or engagement of said pivoted members and arms.

3. In a wringer, in combination, a frame having a head member, stationary and movable wringer rolls therein, spring members for pressing the movable roll against the stationary roll, locking members pivoted on the head member of the frame intermediate the center and ends thereof, each provided with a hooked portion, screw members supported in the pivoted members in a position to engage the spring members and means for effecting engagement or disengagement of the frame and the pivoted members including a member rotatable on a vertical axis on the head member, arms eccentrically connected thereto and engageable with the hooked portions of the pivoted members whereby the turning movement of the former will move the arms into or out of engagement with the pivoted members.

4. In a wringer, in combination, a frame, stationary and movable wringer rolls therein, spring members for pressing the movable roll against the stationary roll, members pivoted to the frame, each provided with a hooked portion, screw members positioned to engage the spring members and supported in the pivoted members, locking arms slidably supported on the frame and engageable with the hooked portions of the

pivoted members, and means for shifting the locking arms into engagement with or disengagement from the pivoted members.

5. In a device of the class described, in combination, frame members, stationary and movable rolls, spring members mounted in the frame members and applying pressure to the outer ends of the movable roll, a head portion, members having catch portions and 10 pivoted intermediate the center and ends of the head portion having their outer ends

provided with screws for engaging said spring members, locking means including laterally extending arms projectible to engage said catch portions and means for releasing the tension on said movable roll including a release handle rotatable on a vertical axis on said frame and means attached thereto for withdrawing said laterally extending arms from said catch portions. 15 20

In testimony whereof I affix my signature.
SIMON E. SCHROEDER.
